E. M. LOW,
REPRODUCER FOR TALKING MACHINES,
APPLICATION FILED MAY 12, 1919.

1,424,838.

Patented Aug. 8, 1922.

INVENTOR
E. M. Low

UNITED STATES PATENT OFFICE.

EVERETT M. LOW, OF BROOKLYN, NEW YORK.

REPRODUCER FOR TALKING MACHINES.

1,424,838.

Specification of Letters Patent. Patented Aug. 8, 1922.

Application filed May 12, 1919. Serial No. 296,622.

To all whom it may concern:

Be it known that I, EVERETT M. Low, citizen of the United States, residing at Brooklyn, in the county of Kings and State 5 of New York, have invented certain new and useful Improvements in Reproducers for Talking Machines, of which the following is a specification.

My invention relates to that class of devices known as reproducers for talking machines in which sounds are reproduced from sounds previously recorded on a record.

The object of my invention is to provide an instrument which will reproduce faithfully, sounds as they are recorded, and prevent the introduction of elements into the reproduced sounds that are not in the record or other source of reproduction.

I attain this object by the device illustrated in the accompanying drawing in which:

Figure 1 is a side view.

Figure 2 is an edge view looking in direction of arrow *y*, Fig. 1, shown sectioned 25 on line *x*—*x*, Fig. 1;

Figure 3 is an edge view looking in direction of arrow 2, Fig. 1 the needle holder being removed, the better to show other parts;

Figure 4 is a view of the bridge *f*.

Fig. 5 is an elevation of the bracket *e*.

Referring to the drawing in which similar reference characters refer to the same parts throughout the several views;

a, is a sound box having the diaphragm *a*², held between rings *a*³ and *a*⁴, of rubber, paper or similar materials and is secured by the metal ring *a*⁵, in a manner well known in the art.

The sound box *a* has the hub *a*⁶, as shown in Fig. 2, the bore *a*⁷ being shown in dotted lines, for attachment to the tone arm of a talking machine in the usual manner.

b, is a lever having at its end *b*², the needle holder *b*³ and the needle *b*⁴.

c, is a tension bar which rests on the lever *b* at its ends *c*², and *c*³, the tension bar being cut away between the ends *c*² and *c*³ to reduce the contact surface and give it a yielding tension under pressure.

d, is a bracket secured to the sound box *a*, serving as a support for the fulcrum *d*²; the cap *d*³, and the screws *d*⁴, and *d*⁵; these parts together with the tension bar *c*, serve 55 as a support and a confining means for the lever *b*, near its end *b*².

e, is a second bracket similar to the bracket *d*, the bracket *e* being secured to the sound box *a* and serving as an equalizing support for the lever *b*, at its end *b*⁵. 60

The bracket *e*, has the cap *e*², and the screws *e*³, and *e*⁴, and the equalizing blocks *e*⁵ and *e*⁶.

The bracket *e* is shown in Fig. 2 as having one side broken away to more clearly show 65 the blocks *e*⁵, and *e*⁶.

f, is a bridge contacting with the lever *b*, at *f*², and with the diaphragm *a*², at *f*³, and *f*⁴, the bridge being cut away between *f*³, and *f*⁴, to reduce the amount of contact surface with the diaphragm *a*². The bridge at "*f*³" and "*f*⁴" contacts with the diaphragm at points of greatest vibratility or about midway between the center and the periphery of the diaphragm; the radial distance from the center when the diaphragm has the greatest vibratility being between 70 four and five tenths of the radius.

The lever *b* is a rigid bar, that is, it is not flexible or springy and is preferably of 80 glass, as glass is elastic and returns quickly and positively to its normal state, after being subjected to an impact or disturbance of its structure.

Other materials may be used such as 85 ivory, hardened steel or hard wood but as far as I have been able to determine, glass meets the requirements better than any other material.

The lever *b*, when used in a reproducer 90 for a talking machine for the reproduction of sound from a record, is provided at its end *b*², with a needle holder *b*³ and a needle *b*⁴, similar to ones used in the art.

The lever *b*, is supported on the fulcrum 95 *d*², resting on the bracket *d*, attached to the sound box *a*.

The fulcrum *d*², is preferably of hard wood or any hard now-vibratile substance; or a pivot may be used instead of the fulcrum *d*, shown in the drawing.

The lever *b*, rests on the bridge *f*, and the bridge *f*, rests on the diaphragm *a*², the bridge *f*, is preferably of hard wood and may be at the center of the diaphragm *a*², as 105 shown but this is not essential as it may be located at some distance from the center and produce practically the same results, except the bridge *f* is made shorter and has a single contact point with the diaphragm *a*², 110 when there is an advantage in locating it off center, which will produce more overtones.

The tension bar c , is preferably of hard wood and rests at its ends, c^2 , and c^3 , on the lever b , the end c^2 , being between the fulcrum d^2 , and the end b^2 , of the lever b , and 5 the end c^3 , of the tension bar c , being at a greater distance from the fulcrum d^2 , than is the end c^2 , of the tension bar c .

The fulcrum d^2 , is located about under the cap d^3 , the locating of the fulcrum d^2 , 10 and the tension bar c , in relation to the lever b , and the cap d^3 , being such as to produce a firm contact of the lever b , with the fulcrum d^2 and a lesser contact of the lever b , with the bridge f , to force the bridge f , on 15 the diaphragm a^2 , sufficient to give the diaphragm a^2 , a slight tension.

The lever b , at its end b^5 , is held between the equalizing blocks e^5 , and e^6 , the equalizing blocks e^5 , being forced on to the lever b 20 and the lever b on to the equalizing block e^6 , and the equalizing block e^6 , on to the bracket e , by the cap e^2 , and the screws e^3 , and e^4 .

The equalizing blocks e^5 , and e^6 , are made 25 preferably of wood and rubber, the wood being in contact with the lever b , other materials may be used, as soft wood, cork or leather.

The equalizing blocks and their co-acting 30 parts are for the purpose of equalizing the tension on the diaphragm a^2 ; if there is too great a tension on the diaphragm a^2 , the block e^6 , would be made thicker and if the tension on the diaphragm a^2 , is not great 35 enough the block e^6 , would be made thinner, the cap e^2 , being adjusted according to the thickness of the block e^6 , by means of the screws e^3 , and e^4 .

The object of this equalizing device is to 40 correct any deviation from the correct tension of the diaphragm produced by the lever b , through the tension bar c , the cap d^3 , and screws d^4 , and d^5 , and to confine the lever b , at its end b^5 , between slightly yielding 45 clamps by which rebounding of the lever b and over vibration of the diaphragm a^2 , is prevented.

I have specified in each instance the kind 50 of material of which the several parts are preferably composed, I do not limit myself to any particular material; as the tension bar c , is made preferably of wood for no other reason than to avoid the production of unrhythmical vibrations by the contact of 55 highly vibrative materials.

It is obvious that the tension bar c , might 60 be made of metal if its contacts with other vibrative parts were insulated by the introduction of thin pieces of non-vibrative material.

Having thus described my invention what I claim and desire to secure by Letters Patent is:

1. A sound box having a diaphragm, a 65 lever adapted to receive vibrations, a bridge

between the lever and the diaphragm, the lever having an incompressible support on one side of the sound box and extending across to and having a second support on the opposite side of the sound box and a confining 70 means for rigidly retaining the lever on the said incompressible support and a second confining means for retaining the lever on the said second support.

2. A sound box having a sound emitting 75 member, a lever adapted to receive vibrations, a connection between the lever and the sound emitting member, a support on the sound box for the said lever, a confining means for retaining the lever on the support 80 and on the connection and the connection on the diaphragm; the said confining means including a tension bar having a plurality of contacts with the lever, the said contacts being so disposed as to cause the lever under 85 the actions of the compressing means to be forced into a firm contact with the support and into a less firm contact with the connection; a second support on the sound box and a second confining means for retaining the 90 lever on the said second support and equalizing means to equalize the tension on the diaphragm produced by the connection, the lever, and the confining means.

3. A sound box having a diaphragm, a 95 lever adapted to receive vibrations, the said lever being fulcrumed on the sound box, the fulcrum engaging one side of the lever and a tension bar engaging the other side of the lever, the tension bar having contacts at 100 its ends, the said contacts straddling the said fulcrum, a bridge connecting the lever and the diaphragm and means for applying pressure to the tension bar to force the lever against the bridge and the bridge against 105 the diaphragm.

4. A sound box having a diaphragm, a lever provided with a needle and a bridge between the lever and the diaphragm, the lever having an incompressible support on 110 one side of the sound box and extending across to and having a second support on the opposite side of the sound box, a confining means for retaining the lever on the said incompressible support and a second confining means for retaining the lever on the said second support, the said second support having an equalizing means to equalize the tension on the diaphragm produced by the lever and the confining means acting on the bridge and 115 on the diaphragm.

5. A sound box, having a diaphragm, a lever having a fulcrum on one side of the sound box, a bridge between the lever and the diaphragm, a tension bar and compressing means for the purpose of forcing the lever onto the fulcrum and onto the bridge, and on the opposite side of the sound box an equalizing means to equalize the tension of 125 the diaphragm produced by the action of the 130

tension bar and its co-acting elements on the lever and the bridge.

6. A sound box having a sound emitting member, a lever adapted to receive vibrations, a connection between the lever and the sound emitting member, a support for the lever, on the sound box, a tension bar overlying the lever and the support and means for forcing the tension bar on to the lever and the lever on to the support, the tension bar having a plurality of contacts with the lever, one of the contacts being at a greater distance from the said connection than the distance of the support from the 15 said connection.

7. A sound box having a sound emitting

member, a lever adapted to receive vibrations, a support on the sound box for the said lever, a connection between the lever and the sound emitting member; a tension 20 bar having a plurality of contacts with the lever and means for forcing the tension bar on to the lever and the lever on to the support and on to the connection, the contacts of the tension bar with the lever being disposed in such manner as to cause the lever to be forced into a firm contact with the support and into a less firm contact with the said connection to give a tension to the dia- 25 phragm.

In testimony whereof I affix my signature.

EVERETT M. LOW.
